(57) **CLAIM**

I claim the ornamental design for motor vehicle exhaust tip,
as shown and described.

DESCRIPTION

FIG. 1 is a perspective view of a vehicle exhaust tip showing
my new design with the claimed vehicle exhaust top
attached to a vehicle tail pipe, which is shown in broken
lines for illustrative purposes only and does not form a part
of the claimed invention.

FIG. 2 is a right side elevational view of the vehicle exhaust
tip shown in FIG. 1, the left side being a mirror image of the
right side, and the top and bottom being identical to the right
side.

FIG. 3 is a front end elevational view of the vehicle exhaust
tip shown in FIGS. 1 and 2; and,

FIG. 4 is a rear end elevational view showing the circular
shape of the vehicle exhaust tip shown in FIGS. 1-3, which
is shown in broken lines for illustrative purposes only and
does not form a part of the claimed invention.
